UNITED STATES PATENT OFFICE

154,759

DESIGN FOR A FINGER RING

Eugene G. Fitzgerald, Pinson, Ala., assignor to
L. G. Balfour Company, a corporation of Mas-
sachusetts

Application March 14, 1949, Serial No. 1,396

Term of patent 14 years

(Cl. D45—10)

To all whom it may concern:

Be it known that I, Eugene G. Fitzgerald, a citizen of the United States of America, residing at Pinson, county of Jefferson, State of Alabama, have invented a new, original, and ornamental Design for a Finger Ring, of which the following is a specification, reference being had to the accompanying drawing, forming a part thereof.

Fig. 1 is a top plan view of a finger ring, showing my new design;

Fig. 2 is a side elevation thereof;

Fig. 3 is an elevation of one edge of the ring; and

Fig. 4 is an elevation of the opposite edge from that shown in Fig. 3.

I claim:

The ornamental design for a finger ring, substantially as shown.

EUGENE G. FITZGERALD.
